PLLC(57) **CLAIM**

We claim the ornamental design for a sleeve for a syringe device, as shown and described.

DESCRIPTION

FIG. 1 is a perspective view at an angle from the front of the sleeve for a syringe device.

FIG. 2 is a perspective view at an angle from the rear of the sleeve for the syringe device.

FIG. 3 is a side view of the sleeve for the syringe device.

FIG. 4 is a side view rotated by 90° compared to FIG. 3 of the sleeve for the syringe device.

FIG. 5 is a front view of the sleeve for the syringe device; and,

FIG. 6 is a rear view of the sleeve for the syringe device.
